(57) **CLAIM**

The ornamental design for a flowing water sterilization module, as shown and described.

DESCRIPTION

FIG. 1 is a front, top, left perspective view of a flowing water sterilization module showing our new design;

FIG. 2 is a rear, bottom, right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is left side elevational view thereof.

The broken lines illustration portions of the flowing water sterilization module which form no part of the claimed design.
